UNITED STATES PATENT OFFICE.

EDMUND T. CHURCH, OF NEW ROCHELLE, NEW YORK.

DESIGN FOR A KNITTED OR CROCHETED TIE.

43,519.

Specification for Design.

Patented Feb. 11, 1913.

Application filed September 30, 1912. Serial No. 723,236. Term of patent 7 years.

To all whom it may concern:

Be it known that I, EDMUND T. CHURCH, a citizen of the United States, residing at New Rochelle, Westchester county, and State of New York, have invented a certain new, original, and ornamental Design for Knitted or Crocheted Ties, of which the following is a specification, reference being had therein to the accompanying drawing, forming part thereof.

The figure is a front view of a tie (not tied), showing my new design.

I claim:

The ornamental design for a knitted or crocheted tie, as shown.

EDMUND T. CHURCH.
